UNITED STATES PATENT OFFICE.

ROBERT BURGESS, OF NEWTON CENTER, MASSACHUSETTS, ASSIGNOR OF ONE-HALF
TO JOSEPH H. JONES, OF WINTHROP, MASSACHUSETTS.

CAP-SPINNING FRAME.

Application filed December 26, 1922. Serial No. 608,309.

To all whom it may concern:

Be it known that I, ROBERT BURGESS, a citizen of the United States, residing at Newton Center, in the county of Middlesex, 5 State of Massachusetts, have invented a certain new and useful Improvement in Cap-Spinning Frames, of which the following is a specification, reference being had therein to the accompanying drawings.

10 The invention comprises improvements in cap-spinning devices of the revolving- or live-cap class on the order of those which are shown, etc., in U. S. Letters Patent No. 1,020,179, granted March 12, 1912, for improvement in devices for spinning and twisting yarn; No. 1,230,097, granted June 19, 1917, for improvement in devices for spinning and twisting textile fibers; No. 1,285,598, granted Nov. 26, 1918, for improvement in devices for spinning and twisting textile fiber; No. 1,294,371, granted Feb. 18, 1919, for improvement in cap-spinning devices; No. 1,385,078, granted July 19, 1921, for improvement in cap-spinning frames; No. 1,401,705, granted Dec. 27, 1921, for improvement in cap-spinning frames; No. 1,416,356, granted May 16, 1922, for improvement in cap-spinning frames; No. 1,434,003, granted Oct. 31, 1922, for improvement in cap-spinning devices and No. 1,445,291, granted Feb. 13, 1923, for improvement in cap-spinning frames.

Organized spinning devices on the order of those of the patents referred to comprise 35 a cap mounted upon the blade or barrel of a revolving spinning element (spindle or bobbin), revolved thereby and movable longitudinally thereof, and one or more so-called pivots or pivot-wheels co-acting with 40 the cap.

In the devices of the patents aforesaid the cap is mounted upon the spinning element through its upper end or head end being furnished with an internal bearing 45 which has a close or easy sliding fit upon the blade or barrel of the spinning element. The easy sliding fit permits the cap to gravitate downward upon the said blade or barrel until it is supported by the pivot-wheel or pivot-wheels. It also permits the 50 traverse movements of the cap up and down upon the blade or barrel which are required to take place for the distribution of the spun

yarn upon the blade or barrel in being wound thereon. The pivot-wheel or pivot-wheels cooperating with a cap are revolvably mounted on a support or supports carried by a rail to which in practice vertical traversing movements are given. In the 55 operation of the spinning devices the yarn being spun passes down alongside a cap and around the edge or lip of the bottom of the cap to the spinning element, upon which latter it is wound. As the rail goes up, the cap is raised by the pivot-wheel or pivot-wheels upward along the blade or barrel 60 of the spinning element. As the rail goes down, the cap gravitates downward upon the said blade or barrel, following the pivot-wheel or pivot-wheels downward. 70

In the case of the live-cap spinning devices of the earlier of the patents aforesaid, the cap is positively revolved in unison with the revolving spinning element, at the same speed as the latter, through the cap being 75 in sliding clutch engagement with the blade or barrel of the spinning element by means of a splined clutch connection, usually a key and groove. The pivot-wheel or pivot-wheels is or are wheels or disks with which 80 the cap makes contact vertically. In the case of later instances, the splined key and groove clutch for causing the cap to be positively rotated being retained, the pivot-wheel or pivot-wheels, in addition to being 85 adapted to support the cap vertically, is or are formed and arranged to operate, through contact with the cap peripherally, to prevent the cap from becoming locked to the blade or barrel of the spinning element, 90 in a manner which would interfere with free vertical movement of the cap up and down upon the said blade or barrel in conformity with the up and down movements of the traverse. In use it was found in all these 95 instances that vibration of the spindle and other causes interfered with reliability of action of the cap; and by reason of the cap being revolved at the same rate of speed as the spinning element the cap had no effect in 100 producing retardation of the circling movement of the yarn in being spun, so as to promote the winding of the yarn upon the spinning element, so that various expedients were employed to retard the yarn in its revolution with the spinning element to cause 105

it to wind upon the latter. In the case of still later instances the splined or key-and-groove clutch has been omitted, and for the purpose of ensuring rotation of the cap 5 the pivot-wheel or pivot-wheels cooperating with the latter has or have been arranged, etc., to cant or tilt the cap slightly relative to the blade or barrel of the spinning element, so as to cause the bearing in the cap 10 head to cramp or bind a little upon said blade or barrel. In the case of a frictionally driven cap this cramping or binding serves to cause the cap to start promptly into rotation in starting up the spinning 15 frame after a stoppage of the frame, or in starting up the individual spinning element after piecing up a broken end of yarn. The canting or tilting has been occasioned through engagement of the periphery of an 20 external lateral bearing member constituted by a pivot-wheel with the outer side of the periphery of the cap near the lower edge of the cap. Thereby the cap has been given a slight tilt away from the lateral bearing 25 member, such tilt operating to bring the lower portion of the central bearing of the cap-head into close contact with that side of the spinning element which is adjacent said lateral bearing member, and also operating 30 to cause the spinning element to be frictionally gripped between upper and lower portions of said central bearing. However, canting or tipping of a cap, and resultant cramping or binding of the same upon a 35 spinning element, have the drawback that they clutch or lock the cap to the spinning element in such manner as to prevent the free relative axial movement that is necessary for the distribution of the yarn up 40 and down upon the spinning element, i. e., as the traverse occurs. Such canting or tipping also results in the cap being caused to rotate upon an axis that is slightly inclined with respect to that on which the 45 spinning element rotates, so that the cap rotates out of true concentricity with the blade or barrel of the spinning element. More or less irregularity of action, vibration and chattering, and more or less accidental up and down movement of the cap 50 relative to the spinning element are observed, all of which it is important and advisable to eliminate. Another drawback of the cramping or binding incident to the 55 canting or tipping of the cap relative to the spinning element is the tendency to cause the cap to revolve at the same speed with the spinning element. This tendency prevents the retardation of the cap which 60 is necessary in order to cause it to revolve more slowly than the spinning element so as to secure satisfactory winding. It is important that the cap should revolve more slowly than the spinning element in order 65 that the yarn passing around its lower edge

to the spinning element may be caused to wind upon the latter.

The leading general object of the invention is to provide live cap devices which will operate satisfactorily without canting 70 or tipping of the cap relative to the axis of the spinning element, and consequently without cramping or binding of the cap upon the spinning element, while securing in operation proper and satisfactory performance of the important functions of so-called pivots or pivot-wheels, namely (1) neutralizing the tendency of the cap and spinning element to become locked together by centrifugal action so as to prevent one 75 thereof from moving axially with respect to the other; (2) effecting in the case of caps which are driven by frictional engagement a sufficient retardation of the speed of rotation of a cap to cause the winding of the 80 yarn, as it is spun, upon the spinning element; and (3) governing the position of the cap vertically during the traverse movements by which the yarn that is in process 85 of being spun and wound upon the bobbin 90 is distributed along the said blade or barrel.

The invention eliminates the tendency aforesaid to canting or tipping of the cap relative to the axis of the spinning element with which it is associated in operation 95 through so relating the pivot or pivot-wheel with respect to the internal bearing of the cap that the pivot or pivot-wheel touches the exterior of the cap in a line extending radially of the cap through the said internal bearing, so that such lateral pressure as may take effect upon the exterior of the cap shall act directly through the said bearing portion without deflecting or tilting the axis of the cap with relation to the axis of the spinning element. Thereby the invention eliminates the cause of canting or tilting of the cap and resulting drawbacks, thus eliminating clutching such as tends to prevent axial movement of the cap; also securing regularity of action, reducing vibration, and diminishing chattering and the accidental up-and-down dancing motion of the cap heretofore observable. The invention furthermore alleviates the similar irregularities, 110 etc., attributable to want of concentricity of the spinning element and the cap with the axis of rotation.

As will be apparent to those skilled in the art, and familiar with spinning frames and spinning conditions, the results which are attained in practice by means of my invention are conducive to better spinning conditions and longer life of the spindle or other spinning element.

The invention includes clutching means adapted to cause a cap to rotate in unison with its spinning element at those times when this action is desirable or necessary, as for instance on first starting-up a spinning- 130

frame after a stoppage, or following stoppage of the spinning element for any purpose whatever, as for piecing-up, and further adapted to thereafter cease to act and 5 leave the cap to be driven through frictional engagement of the spinning element therewith. It further includes the combination with a live cap of a clutch of special construction.

10 In the drawings,—

Fig. 1 is a view in side elevation of certain parts of a cap-spinning frame, with various rails in cross-section, illustrating one embodiment of the invention, and the 15 connection in which the invention is applied and used in practice.

Fig. 2 is a partly sectional view, on an enlarged scale, of certain of the elements that are shown in Fig. 1.

20 Fig. 3 is a side elevation of the bearing and clutch of Fig. 2, detached.

Fig. 4 is a view in horizontal section in the plane indicated by line 4, 4, in Fig. 3.

25 Fig. 5 is a plan view of the said bearing and clutch.

Fig. 6 is a view thereof in vertical section in the plane indicated by line 6, 6, of Fig. 5.

30 Figs. 7, 8, 9, 10, 11, and 12 are views showing modifications, Figs. 7 and 8 being partly sectional.

Figs. 13 and 14 are diagrams illustrating different combinations of caps and pivots or pivot-wheels.

Referring first to Fig. 1 of the drawings,—

35 Old and well-known parts shown therein comprise a thread-board 1 having hinged thereto at 2, in usual manner, a block 3 carrying the guide 4 for the yarn α between the front rolls (not shown) and the devices 40 by which the yarn is twisted. Also, a spindle-rail 5, a spindle-bearing support 6 mounted thereon, and a spinning-spindle 7 of sleeve-whirl type mounted in said bearing-support and provided with a banding 45 whirl 7^a around which passes a spindle driving band 8 by means of which the spindle is rotated; and a quill or bobbin 9 mounted upon the said spindle. The drawings show, further, a cap 10 mounted upon the upper 50 portion of the said quill or bobbin and, as explained hereinafter, frictionally driven thereby so as to revolve in unison therewith, and a cap-controlling pivot, pivot-wheel, or whirl 12 in rolling peripheral contact with 55 the cap. At 13 is a rail, which is substantially like the ring-rail of a ring-spinning frame, and which carries the support 14 of the pivot, pivot-wheel, or whirl 12.

In Fig. 1, etc., the cap is cone-shaped and 60 flares upwardly as in Letters Patent No. 1,385,078 and No. 1,401,705, it being of the specific form shown, described and claimed in the latter patent, and the upper portion of the cap overhangs and touches the peripheral 65 portion of the pivot, pivot-wheel, or whirl

12, whereby the cap is supported vertically by means of the periphery of the pivot, pivot-wheel, or whirl.

70 Preferably, and as shown in Fig. 2, the head of the cap 10 is provided with a bushing 101, the interior bore of which is proportioned to fit loosely upon the blade or barrel of the spinning element, which last in this instance is the quill or bobbin 9. The said fit is sufficiently loose to permit the cap 75 to slide up or down upon the said blade or barrel, and also to permit slight rocking or tilting of the cap relative to the axis of the spinning element to occur without resulting cramping or clutching of the cap to the blade 80 or barrel of said element. The fit of the internal cap-bearing, while sufficiently close to enable the cap to be rotated by means of the frictional engagement between the contacting surfaces of the blade or barrel and 85 bushing, nevertheless is such as to permit the cap to gravitate downward upon the spinning element in question until the cap is supported through its flaring periphery 90 resting upon the cap-contacting peripheral portion of the pivot, pivot-wheel, or whirl 12, and also to permit the traverse movements of the cap relative to the said blade or barrel which are required to take place for 95 the distribution of the twisted yarn upon such blade or barrel in being wound thereon. These traversing movements are due in practice to vertical movements of rail 13 relative to rail 5, or vice versa.

99 Figs. 1 and 2 show the cap-engaging peripheral portion of the pivot, pivot-wheel, or whirl 12 located as aforesaid, in accordance with one part of the invention, at such a height relative to the internal bearing of the cap upon the spindle or blade of the 100 bobbin 9 that, as stated previously herein, the pivot, pivot-wheel, or whirl touches the periphery of the cap in a line extending radially of the cap through the said internal bearing. Thereby is attained the result 105 which has been mentioned; namely, such lateral pressure as may take effect upon the exterior of the cap acts directly through the bearing portion without deflecting or tilting the axis of the cap with relation to the axis 110 of the spinning element. This same relationship exists in the case of each of the 115 modifications illustrated in Figs. 7, 8, 9, 10, and 11.

120 The improved clutching means constituting one portion of the invention is illustrated in Figs. 2, 3, 4, 5 and 6 of the drawings.

Such clutching means embodies, as in Letters Patent No. 1,445,291, granted Feb. 13, 1923, for improvement in cap-spinning frames, upon my application filed March 14, 1922, Serial No. 543,586, the principle of employing a plurality of clutch-elements, 125 preferably balls, arranged in a circular series, lightly held pressed inward for fri- 130

tional contact with the periphery of the blade or barrel of the spinning element, and adapted to move outward under the action of centrifugal force. Clutch-elements such as referred to are represented at 15, 15, Figs. 2 to 6. In accordance with the present invention, I employ two circular series of the said clutch-elements, one above the other, as shown clearly in Figs. 2 and 6, and preferably so disposed that one of the said series shall be located above the point of contact between the exterior of the cap and a pivot, pivot-wheel, or whirl, and the other series shall be located below such point. The two circular series of clutch-elements, one above the other, tend through their contact with the exterior of the blade or barrel of the spinning element to maintain the axis of the cap in substantial parallelism with the axis of the spinning element, and substantially coincident therewith. Thereby greater steadiness of the cap in rotation, and other advantages, are attained, and the tendency of the cap to become cramped upon the said blade or barrel, so as to interfere with the required differential rate of rotation, and with free vertical movement of the cap upon such blade or barrel, are obviated.

Herein I have represented each series of the clutch-elements, shown as balls as in Letters Patent No. 1,445,291 aforesaid, and as preferred, held in place in connection with bushing 10 by being contained in sockets in said bushing, and gently pressed inward by means of a light spring strip 16 in the shape of a split annulus which encircles the series of clutch-members and contacts with the outer portions thereof. For the accommodation of the spring 16, the bushing is externally grooved at 17, 17. The construction adopted by preference in practice is illustrated in Figs. 2 to 6, and in the case thereof the bushing, two series of clutch-members, and springs, constitute a clutch-unit. The connection of the said clutch-unit with the body of the cap may be established by molding the body around the bushing, when such body is made of plastic material, such for instance as bakelite, and produced by molding. Or, as shown, the bushing may be externally screw-threaded, and the central opening in the head of the cap may be correspondingly threaded internally, and the clutch-unit may be screwed into place.

As in Letters Patent No. 1,445,291, normally the clutch-elements are gently pressed inward so as to engage lightly with the surface of the blade or barrel of the spinning element, to aid by clutch-action to cause the cap to begin to revolve simultaneously with the spinning element when the spinning frame is started up from a state of rest, as after a stoppage, or when the particular spinning element starts to rotate after a broken end of yarn has been pieced up; and

they are permitted to displace outward by centrifugal action so as to reduce the clutching action after the cap has attained a predetermined speed of rotation, and leave the cap free to be driven through frictional engagement with the blade or barrel of the spinning element, and to revolve at a differential rate relative to such element. 70

The clutch-elements of the present invention have all the advantages that are set forth in Letters Patent No. 1,445,291. 75

Preferably the clutch elements of the upper series alternate in circular succession with those of the lower series, as shown in Figs. 5 and 6. 80

The first feature of the present invention, namely that of peripheral contact of the exterior of the cap with the periphery of a pivot, pivot-wheel, or whirl 12 in a line extending radially of the cap through the internal bearing for the blade or barrel of the spinning element, is shown in Fig. 7 associated with a clutch-device having a single circular series of radially-movable clutch-elements. It is shown in Fig. 8 associated with a cap having a simple sleeve-bearing 102. It may be associated with a cap 103, Fig. 9, and pivot, pivot-wheel, or whirl 121 in the case of which the cap is furnished at its head or top with a projecting rim 104 making contact with the downwardly flaring, conical, pivot, pivot-wheel, or whirl. In such case the contact will be, as in the other instances, in a line extending radially of the cap through the internal bearing. Fig. 10 shows a cap 105 having arranged to cooperate with its upwardly flaring portion 106, a pivot, pivot-wheel, or whirl 122 revolving on an inclined axis. Fig. 11 shows a cap 107 having arranged to cooperate with its upwardly flaring portion 108 a pivot, pivot-wheel, or whirl 123 revolving on a horizontal axis. 95

Fig. 12 shows an embodiment of the first feature of the invention in which a cap, 109, has arranged to cooperate with its flaring head portion a series of pivots constituted by a circular series of balls, 124, 124, mounted in an annular holder 125 which in practice is supported in convenient manner upon the rail 13. While in the case of all the illustrated forms of embodiment of the first feature of the invention the pivots, pivot-wheels or whirls operate to restrain ballooning of the yarn in process of being spun, the annular arrangement of Fig. 12 is the most effective in such respect. 110

In some cases I contemplate employing two wheel-like pivots, pivot-wheels, or whirls 12, 12, in conjunction with a cap, as in Fig. 13, both of the same arranged to engage with the cap in conformity with the first feature of the invention. In other cases I may employ three thereof, arranged as in Fig. 14. 115

Speaking generally, the form, etc., of the clutch-members may be varied in practice. They are rounded to facilitate the movement of a cap down into place over the upper end of the spinning element to which it is applied. When revoluble, as in the case of balls, they have a rolling contact with the periphery of the spinning element 9, which renders the clutching action gentler and more uniform. Such rolling contact facilitates the movement of a cap vertically upon its spinning element as the traverse rail rises and falls, and it obviates injury, as for instance to the spinning element, cap, or pivot, as well as avoids interference with the ascending movement of the pivot-supporting rail, in case a spindle-band breaks and the spinning element ceases to rotate, in which case the centrifugal action of the clutch-members terminates and the clutch-devices might cling tightly to the spinning element and tend to prevent the cap from moving vertically relative to the latter if the rolling contact did not provide for such relative movement.

What is claimed as the invention is:—

1. In cap-spinning devices, the combination with a spinning element, and a live cap actuated by the said element, having an internal bearing surrounding the blade or barrel of such element, of a "pivot" cooperating radially with the exterior of the cap in a line extending radially of the cap through the said internal bearing.

2. In cap-spinning devices, the combination with a spinning element, and a live cap actuated by the said element, having an internal bearing surrounding the blade or barrel of such element, of a revoluble "pivot" cooperating radially with the exterior of the cap in a line extending radially of the cap through the said internal bearing.

3. In cap-spinning devices, the combination with a spinning element, and a live cap actuated by the said element, having an internal bearing surrounding the blade or barrel of such element, and having also a vertically flaring periphery, of a "pivot" cooperating with the said flaring periphery in a line extending radially of the cap through the said internal bearing.

4. In cap-spinning devices, the combination with a spinning element, and a live cap actuated by the said element, having an internal bearing surrounding the blade or barrel of such element, and having also a vertically flaring periphery, of a revoluble "pivot" cooperating with the said flaring periphery in a line extending radially of the cap through the said internal bearing.

5. In cap-spinning devices, the combination with a spinning element, and a live cap having a vertically flaring periphery and an internal bearing loosely fitting the blade or barrel of the spinning element,

said cap rotated in unison with the spinning element through frictional engagement, of a "pivot" cooperating with the said flaring periphery in a line extending radially of the cap through the said internal bearing. 70

6. In cap-spinning devices, the combination with a spinning element, and a live cap having a vertically flaring periphery and an internal bearing loosely fitting the blade or barrel of the spinning element, said cap rotated in unison with the spinning element through frictional engagement, of a revoluble "pivot" cooperating with the said flaring periphery in a line extending radially of the cap through the said internal bearing. 75

7. In cap-spinning mechanism, the combination with a revoluble spinning element and a live cap mounted upon the blade or barrel of such element, of an upper and a lower circular series of clutch-elements, each circular series comprising a plurality of said clutch-elements which normally make light frictional contact with the said blade or barrel and are permitted to move outward under the action of centrifugal force. 80

8. In cap-spinning mechanism, the combination with a revoluble spinning element, and a live cap mounted upon the blade or barrel of such element, of an upper and a lower circular series of revoluble clutch-elements which normally make light frictional contact with the said blade or barrel and are permitted to move outward under the action of centrifugal force. 85

9. In cap-spinning mechanism, the combination with a revoluble spinning element, and a live cap mounted upon the blade or barrel of such element, of a friction clutch carried by said cap comprising an upper and a lower series of balls which normally make light frictional contact with said blade or barrel and move outward from the axis of the blade or barrel under the action of centrifugal force. 100

10. In cap-spinning mechanism, the combination with a revoluble spinning element, and a live cap mounted upon the blade or barrel of such element, of a clutch-unit, carried by the said cap comprising a bushing, an upper and a lower series of clutch-members radially movable under the influence of centrifugal force, and a spring encircling each series and lightly pressing the clutch-members thereof inward. 110

11. In cap-spinning mechanism, the combination with a revoluble spinning element, and a live cap having a central opening with an easy sliding fit upon the blade or barrel of such element, of an upper and a lower series of clutch-elements in connection with such opening, each series concentric with the opening, lightly pressed inward for contact with the periphery of said blade or barrel, and adapted to move outward under the action of centrifugal force. 125

12. In cap-spinning mechanism, the combination with a revolute spinning element, and a live cap having a central opening with an easy sliding fit upon the blade or barrel of such element, of an upper and a lower series, of revolute clutch-elements concentric with said central opening, lightly pressed inward for contact with the periphery of said blade or barrel, and adapted to move outward under the action of centrifugal force.
13. In cap-spinning mechanism, the combination with a revolute spinning element, and a live cap having a central opening with an easy sliding fit upon the blade or barrel of such element, of a friction clutch carried by said cap comprising an upper and a lower series of balls lightly pressed inward into contact with said blade or barrel and moving outward from the axis of the blade or barrel under the action of centrifugal force.
14. In cap-spinning mechanism, the combination with a revolute spinning element, and a live cap having a central opening with an easy sliding fit upon the blade or barrel of such element, of a clutch-unit, carried by the said cap comprising a bushing, an upper and a lower circular series of clutch-members radially movable under the influence of centrifugal force, each series having a spring encircling and lightly pressing the clutch-members inward.
15. In cap-spinning mechanism, the combination with a revolute spinning element and a live cap mounted upon the blade or barrel of such element, of an upper and a lower circular series of clutch-elements, each circular series comprising a plurality of said clutch-elements which normally make light frictional contact with the said blade or barrel and are actuated by centrifugal force to reduce the driving action thereof.
16. In cap-spinning mechanism, the combination with a revolute spinning element, and a live cap mounted upon the blade or barrel of such element, of an upper and a lower circular series of revolute clutch-elements which normally make light frictional contact with the said blade or barrel and are actuated by centrifugal force to reduce the driving action thereof.
17. In cap-spinning mechanism, the combination with a revolute spinning element, and a live cap mounted upon the blade or barrel of such element, of a friction clutch carried by said cap comprising an upper and a lower series of balls which normally make light frictional contact with said blade or barrel and are actuated by centrifugal force to reduce the driving action thereof.
18. In cap-spinning mechanism, the combination with a revolute spinning element, and a live cap having a central opening with an easy sliding fit upon the blade or barrel of such element, of an upper and a lower series, of revolute clutch-elements concentric with said central opening, lightly pressed inward for contact with the periphery of said blade or barrel, and actuated by centrifugal force to reduce the driving action thereof.
19. In cap-spinning mechanism, the combination with a revolute spinning element, and a live cap having a central opening with an easy sliding fit upon the blade or barrel of such element, of an upper and a lower series of revolute clutch-elements concentric with said central opening, lightly pressed inward for contact with the periphery of said blade or barrel, and actuated by centrifugal force to reduce the driving action thereof.
20. In cap-spinning mechanism, the combination with a revolute spinning element, and a live cap having a central opening with an easy sliding fit upon the blade or barrel of such element, of a friction clutch carried by said cap comprising an upper and a lower series of balls lightly pressed inward into contact with said blade or barrel and actuated outward from the axis of the blade or barrel by centrifugal force to diminish the driving action.
21. In cap-spinning mechanism, the combination with a revolute spinning element, of a live cap mounted upon the blade or barrel of such element, said cap having an upper and a lower circular series of clutch-elements, each series comprising a plurality of said clutch-elements which normally make light frictional contact with the said blade or barrel, and a revolute pivot cooperating radially with the exterior of the cap in a line extending radially of the cap intermediate the two circular series of clutch-elements.
22. In cap-spinning mechanism, the combination with a revolute spinning element, of a live cap mounted upon the blade or barrel of such element, said cap having an upper and a lower circular series of clutch-elements, each series comprising a plurality of said clutch-elements which normally make light frictional contact with the said blade or barrel and are permitted to move outward under the action of centrifugal force, and a revolute pivot cooperating radially with the exterior of the cap in a line extending radially of the cap intermediate the two circular series of clutch-elements.
23. In cap-spinning mechanism, the combination with a revolute spinning element, of a live cap mounted upon the blade or barrel of such element, said cap having an upper and a lower circular series of revolute clutch-elements which normally make light frictional contact with said blade or barrel, and a revolute pivot cooperating radially with the exterior of the cap in a line extending radially of the cap intermediate the two circular series of clutch-elements.

line extending radially of the cap intermediate the two circular series of clutch-elements.

24. In cap-spinning mechanism, the combination with a revolute spinning element, of a live cap mounted upon the blade or barrel of such element, said cap having an upper and a lower circular series of revolute clutch-elements which normally make light 10 frictional contact with said blade or barrel, and are permitted to move outward under the action of centrifugal force, and a revolute pivot cooperating radially with the exterior of the cap in a line extending radially of the cap intermediate the two circular series of clutch-elements.

25. In cap-spinning mechanism, the combination with a spinning element, of a live cap mounted upon the blade or barrel of 20 such element, said cap having a vertically flaring periphery and an upper and lower circular series of clutch-elements, each series comprising a plurality of said clutch-elements which normally make light frictional contact with the said blade or barrel, and a revolute pivot cooperating with the flare of said periphery intermediate the upper and lower series of clutch-elements.

26. In cap-spinning mechanism, the combination with a spinning element, of a live cap mounted upon the blade or barrel of such element, said cap having a vertically flaring periphery and an upper and lower circular series of clutch-elements, each series comprising a plurality of said clutch-elements which normally make light frictional contact with the said blade or barrel, and are permitted to move outward under the action of centrifugal force, and a 30 revolute pivot cooperating with the flare of said periphery intermediate the upper and lower series of clutch-elements.

27. In cap-spinning mechanism, the combination with a revolute spinning element, 45 of a live cap mounted upon the blade or barrel of such element, said cap having an internal bearing surrounding the blade or barrel of such element and having also in conjunction with the said internal bearing an upper and lower series of clutch-elements, each series comprising a plurality of said clutch-elements which normally make light frictional contact with the said blade or barrel, and a pivot cooperating radially

with the exterior of the cap in a line extending radially of the cap intermediate the two circular series of clutch-elements.

28. In cap-spinning mechanism, the combination with a revolute spinning element, of a live cap mounted upon the blade or 60 barrel of such element, said cap having an internal bearing surrounding the blade or barrel of such element and having also in conjunction with the said internal bearing an upper and lower series of clutch-elements, each series comprising a plurality of said clutch-elements which normally make light frictional contact with the said blade or barrel, and are permitted to move outward under the action of centrifugal force, 65 and a pivot cooperating radially with the exterior of the cap in a line extending radially of the cap intermediate the two circular series of clutch-elements.

29. In cap-spinning mechanism, the combination with a revolute spinning element, of a live cap mounted upon the blade or barrel of such element, said cap having an internal bearing surrounding the blade or barrel of such element and having also in conjunction with the said internal bearing an upper and a lower series of clutch-elements, 80 each series comprising a plurality of said clutch-elements which normally make light frictional contact with the said blade or barrel, and a revolute pivot cooperating with the exterior of the cap in a line extending radially of the cap intermediate the two circular series of clutch-elements.

30. In cap-spinning mechanism the combination with a revolute spinning element, of a live cap mounted upon the blade or barrel of such element, said cap having an internal bearing surrounding the blade or barrel of such element and having also in conjunction with the said internal bearing an upper and a lower series of clutch-elements, each series comprising a plurality of said clutch-elements which normally make light frictional contact with the said blade or barrel, and are permitted to move outward under the action of centrifugal force, 95 and a revolute pivot cooperating radially with the exterior of the cap in a line extending radially of the cap intermediate the two circular series of clutch-elements.

ROBERT BURGESS.
